PASQUALE VESCIOS AND PETER VESCIOS, OF PORT CHESTER, NEW YORK.

SHOE.

1,273,292.

Specification of Letters Patent. Patented July 23, 1918.

Application filed February 23, 1918. Serial No. 218,894.

To all whom it may concern:

Be it known that we, PASQUALE Vescio and PETER Vescio, both subjects of the King of Italy, and both residents of Port Chester, in the county of Westchester and State of New York, have invented new and useful Improvements in Shoes, of which the following is a specification.

This invention relates to shoes, and the main objects of the same are:—to provide a shoe construction with additional material for reinforcing the uppers including the toe-cap; to employ the additional material as a means for connecting the uppers and toe-cap with the sole; and to effect that connection in such a novel manner as to prevent the seepage of water therethrough, there being also in view in this connection the further object of effecting the connection of the uppers with the sole in such manner as to provide for an insole or filling adapted to reinforce the soles for the protection of the foot against cold and dampness.

Another object of the invention is to provide a shoe construction which is adapted not only to protect the feet of the wearer from cold and dampness due to inclement weather, but which also possesses advantages in points of comfort, strength and durability to better supply the needs of soldiers, farmers and others whose duties require them to travel over bad roads, and through rough, wooded or mountainous territory.

With the foregoing objects and others in view, the invention resides in the details of construction and in the arrangement and combination of parts hereinafter described and shown in the accompanying drawings, forming a part of this specification, and in which:—

Figure 1 is a view in perspective of a shoe made in accordance with our invention, a part thereof being broken away in order better to illustrate our improved construction.

Fig. 2 is an enlarged cross sectional view, the same being taken approximately on the line 2—2 of Fig. 1.

Fig. 3 is a similar view, but illustrating a modified construction.

With more particular reference to the accompanying drawings, the numeral 10 is employed to denote a shoe, which includes the usual uppers 11 and the toe-cap 12. Upon the inner side of the uppers 11, we apply an auxiliary or lining strip as 13, the same

beginning preferably at a point as 14, adjacent the juncture of the heel 15 with the body, and extending entirely around the front portion of the shoe including the toe-cap 12 thereof, and terminating on the opposite side of the shoe, similarly adjacent the union of the heel with the body.

This auxiliary strip 13 may thus be applied to overlie or line the uppers 11 and toe-cap 12 with its top edge as 16 extending a considerable distance above the sole as indicated in Fig. 2, although it may be made to extend either higher or lower, as desired, the exact height in particular cases depending very largely upon the character of service for which the shoes are to be used. The lower edge of this auxiliary strip 13 extends beyond the lower incurved edge as 17 of the uppers 11 and likewise of the toe-cap 12 for a sufficient distance to enable it to be bent around the said edge as at 18 and to extend outwardly again as at 19 underlying the edge 17. In this manner we arrange to engage the lower edges of the uppers 11 and of the toe-cap 12 all around in an exterior channel formed by curving inwardly and then outwardly the lower edge of the auxiliary strip 13. This auxiliary strip 13 may be made of leather, rubber, or of any suitable material, and the same is preferably secured to the uppers 11 and toe-cap 12 by means of paste or cement, although any other suitable means adapted to hold them in proper contiguous engagement may be employed.

Connected to the flat outwardly projecting portions 19 of the strips 13, is the sole 20, the connection being preferably effected by stitches as 21 which extend through the inwardly and outwardly projecting portions of the strip 13 as well as through the ends engaged therebetween as best shown in Fig. 2, whereby to bind the ends together with the said sole 20.

The space above the sole 20, extending between the curves or heels 18 of the strip 13, is filled with an insole 22, which may consist of leather, rubber, cork, felt, or combinations thereof, or any filling material suitable for the purpose, this space, however, being thus filled or packed substantially level with the adjacent top sides of the inwardly projecting portions of the strip 13, as illustrated in Fig. 2.

To the sole 20 may be sewed as at 23, or

otherwise secured thereto, the outsole 24, here shown as a single piece of leather, but which may appropriately consist of layers of leather secured or pasted together in the usual way. By thus arranging the auxiliary strip 13, the shoe is materially strengthened to withstand hard service, and the foot effectually protected against cold and dampness. The connection effected between the uppers including the toe-cap and the sole provides, in this embodiment of the invention, three layers of material bound together with the sole, through which the water or moisture must penetrate before reaching the foot, thereby rendering the shoe substantially waterproof.

In Fig. 3, we illustrate a modification of our improved construction. Here the auxiliary strip consists of one large piece of material 25, which lies flat upon the insole 22 and which, after extending upwardly therefrom as at 26 on each side, is bent upon itself as at 27 and thence extending downwardly provides an outer portion 28, interposed between the inner portion 26 and the uppers or toe-cap, the lower edge of said outer portion 28 being curved inwardly and outwardly as in the previous construction, to confine the lower edges of the uppers 11 and toe-cap 12. Under this modified construction, the strip 25 serves as an additional sole, and the side portions 26 and 28 provide two layers of material for the protection of the foot, while four layers of material are sewed or bound together upon the sole 20, the sewing being accomplished as in the previous instance.

Having thus described our invention, what we claim is:—

- 40 1. In a shoe, the combination with the uppers and a sole thereof, of an auxiliary strip over-lying the lower regions of the uppers on the inner side thereof, said strip being curved inwardly and then outwardly to provide an exterior channel within which is confined the lower edges of the uppers, said outwardly projecting strip portions lying flat upon the sole, and means for binding the said inwardly and outwardly projecting portions with the said interposed edges together with the said sole.
- 45 2. In a shoe, the combination with the uppers and a sole thereof, of an auxiliary strip engagedly over-lying the lower inside regions of the uppers, said strip being curved inwardly and outwardly to provide an exterior channel receptive of the lower edges of the uppers, said outwardly projecting portions of the strip lying flat upon the sole, means for binding the inwardly and outwardly projecting portions with the inter-

being approximately level with said inwardly projecting portion.

3. In a shoe, the combination with the uppers including the toe-cap and a sole, of an auxiliary strip lining the lower portions of the uppers and toe-cap, said strip curving inwardly and outwardly to provide an exterior channel receptive of the lower edges of the uppers and toe-cap, the outwardly projecting portions of the strip lying flat upon the sole and means for sewing or otherwise binding the inwardly and outwardly projecting portions with the said engaged edges together and with the sole.

4. In a shoe, the combination with the uppers and connected toe-cap and the sole, of an auxiliary strip connected with and lining the lower portions of the uppers and toe-cap on the inside, said strip being curved inwardly and outwardly to provide an exterior channel within which is confined the lower edges of the uppers and toe-cap, the outwardly projecting portions of the strip lying flat upon the sole, means for sewing or otherwise binding the inwardly and outwardly projecting portions of the strip with the confined edges together and with the sole, and insole material engaged upon the sole between the inwardly and outwardly projecting portions, said insole material rising approximately to the level of the inwardly projecting portions of the strip.

5. In a shoe, the combination of the uppers and connected toe-cap, an auxiliary strip lining the lower portions of the uppers and toe-cap on the inside thereof, said strip being curved inwardly and then outwardly to provide an exterior channel receptive of the edges of the uppers and toe-cap, a sole, and means for binding the inwardly and outwardly projecting portions of the strip with the engaged edges together and with the sole.

6. In a shoe, the combination of the uppers and connected toe-cap, an auxiliary strip lining the lower regions of the uppers and toe-cap on the inside thereof, said strip being curved inwardly and then outwardly to provide an exterior channel receptive of the edges of the uppers and toe-cap, a sole, means for binding the inwardly and outwardly projecting portions of the strip with the said confined edges together and with the sole, and insole material engaged upon the sole between the inwardly and outwardly projecting portions, said insole material rising approximately to the level of the inwardly projecting portions of the strip.

7. In a shoe, the combination of the uppers and a sole formed with an elevated portion providing an exterior recess all around, an auxiliary strip lining the lower regions of the uppers, said strip being curved inwardly and outwardly in said exterior recess to provide an exterior channel receptive of the lower edges of the uppers, and means

for binding the inwardly and outwardly projecting portions including the interposed edges together and with the sole.

8. A shoe having an auxiliary strip lining

5 the uppers, the lower portions of said strip being curved inwardly and outwardly to provide an exterior recess within which to confine the lower edges of the uppers, and means for sewing or otherwise binding the 10 inwardly and outwardly projecting portions together with the edges confined therebetween.

9. In a shoe, the combination with the uppers and a sole formed with an elevated 15 portion providing an exterior recess all around, of an auxiliary strip engaged intermediate its width upon said elevated portion with its opposed sides curving upwardly in conformity with the uppers and curved 20 upon itself and engaged between itself and the uppers and thence extending inwardly and outwardly in said exterior recess to provide an exterior channel receptive of the 25 lower edges of the uppers, said outwardly projecting portion lying flat upon the sole,

and means for binding the inwardly and outwardly projecting portions including the inter-engaged edges together and with the sole.

10. In a shoe, the combination with the 30 uppers including the attached toe-cap and a sole having an elevated portion intermediate its width providing an exterior recess all around, of auxiliary material spread upon the elevated portion with its opposed sides 35 extending upwardly in conformity with the uppers and bent outwardly upon itself and extending downwardly between itself and said uppers and toe-cap and then curved inwardly and outwardly in said exterior recess 40 to provide an exterior channel receptive of the lower edges of the uppers and toe-cap, and means for binding the inwardly and outwardly projecting portions including the 45 interposed edges together and with the sole.

In testimony whereof we have signed our names to this specification.
